UNITED STATES PATENT OFFICE

COLIN THOMPSON ARBUTHNOT SHEARER, OF SPILMANS GROVE, HAYES, ENGLAND

BOOT AND SHOE HEEL

Application filed June 24, 1929, Serial No. 373,222, and in New Zealand April 29, 1929.

This invention has been devised with the object of providing improvements in boot and shoe heels of the class in which detachable wearing surfaces are employed. The invention consists more particularly in the means employed in attaching such surfaces to the heel and which means are designed to provide for the attachment and detachment being effected without the employment of skilled labour. This will enable anyone to replace a worn surface with a new one, in a few moments.

The invention comprises the combination with the heel, and with the thickness of leather or other material forming the wearing surface, of a square or otherwise cornered socket member let into the heel bottom, a female member affixed to the inside face of the wearing surface and shaped to form a neat fit within the socket, and a locking screw pin extending through both socket and female member and adapted to lock the one within the other by an action by which the wearing surface is drawn up closely against the heel bottom. These may, however, be so designed as to allow for a cushion heel being provided for, by the insertion between the heel and the wearing surface, of a strip of resilient material.

The said locking screw pin may be held as a permanent fitting within the heel so that it projects down within the socket and is free to turn while being held from longitudinal movement, and the female member made with a female screw threaded hole to receive such pin, or alternatively, the screw pin may be made as an attachment to the female member and to screw up into a female screw threaded hole in the top of the socket. In either instance, also, the locking portion of the pin and its female threaded receiving hole may be made with mutilated threads, as in gun breech block construction, to allow of the one sliding into or on to the other and then being locked by a partial rotation of the pin.

The invention is illustrated in the accompanying drawings, in which:—

Figure 1 is a sectional side elevation of a heel showing the wearing piece secured there-

to by means in which the locking pin is fitted to remain in the heel.

Figure 2 is a side elevation of the wearing surface and its spigot fitting as designed for such means.

Figure 3 is an underneath plan of the heel, and

Figure 4 a plan of the wearing surface, each with its fitting secured thereto.

A is the heel which is made of any of the usual materials and forms. B is the wearing strip of leather to be secured to the surface of the heel so that it may be removed at will and be replaced by a new one whenever desired.

In the form of the invention shown in the drawings, a metallic plate C is affixed to the bottom of the heel A, to cover whole or part of its surface as may be desired, if covering a part only, being let into such surface so as to be flush therewith, as in the drawings. This plate C is made in one with a socket D that is let into a recess E formed in the heel. The top of the socket is made with a hole F passing through it which hole is plain in the form shown in Figures 1 to 4.

A metallic plate G is also combined with the wearing strip B so that it covers its top side. This plate has formed therewith, a female member H, which is of such a shape and size as to be capable of fitting with a close fit into the socket D when the wearing strip is laid on the heel and to allow of the two surfaces making a close joint.

The said socket and female member are made of any approved shape in sectional plan as to provide that when fitted together, the female member is incapable of turning in the socket. This may be obtained by shaping them of the square form shown in the drawings, or of other approved angular form.

The female member H is made with a female threaded aperture J extending right up through it, and the strip B in preparing it for attachment to this member, is made with a hole through it which then coincides with the aperture J to permit of the blade of a screw driver being inserted.

A screw pin K is provided in each instance. This in the form shown is made with a flange

M on its upper end and is passed outward through the hole F in the socket top prior to the socket being fitted into the heel, so that the flange then lies between the socket and the top of the heel recess E with the pin projecting centrally down in the socket. The fit of the flange is a loose one, thus allowing for the pin being rotated. To provide for such rotation being effected, the bottom end of the pin is made with a screw driver slot. This arrangement provides that to secure the wearing strip to the heel it is placed on the heel so that the female member enters the socket and the pin end enters the threaded aperture J in the female member. Then by turning the pin in the proper direction, the pin will screw into the female member and draw it right in so that the two surfaces will be brought into close locking engagement. The strip may be removed at any time by a reversal of these operations.

This form of fastening will allow for a resilient pad N, of rubber or like material, being placed between the surfaces of the heel A and the metal plate G carrying the wearing surface B, to extend over the full area of their contact. This will give a cushion effect to the heel. The necessary freedom for the wearing surface to move upward is provided for by allowing free spaces between the top of the recess E and the head M of the screw pin, and between the top of the socket D and the female member H.

The plate G to which the wearing surface B is secured may, if desired, be made with a thickened portion G' on a suitable part of its edge, the surface B then being fitted within such portion as shown in order that a uniform bottom face is obtained. This portion G' will then serve as a protector against the tendency, so very common, to wear down on one edge of the heel.

The hole left in the wearing surface for the screw pin K may be filled with wax or other material that may easily be picked out to give access to the pin.

I claim:—

In a heel for boots and shoes, the combination with the heel and with a wearing strip therefor, of a member seated rigidly in said heel and having a socket therein provided with a central aperture in its upper end and formed with angular internal walls; a female member formed with angular external walls and seated in said socket, and having an internally screw-threaded aperture extending vertically through the same; and a threaded bolt formed with a flat head and adapted to extend loosely through the aperture in said socket; said bolt having threaded engagement with the female member for the purpose of locking the same within the socket.

In testimony whereof, I affix my signature.
